Machinery Corporation, Paterson, N. J., a cor-
poration of New Jersey

Application March 4, 1936, Serial No. 66,989
In Great Britain March 23, 1935

12 Claims. (Cl. 164—88)

This invention relates to perforating machines and is herein illustrated as embodied in a machine for operating upon uppers or other parts of boots and shoes, of the type in which the work is advanced by a tool or tools which produce ornamental perforations therein.

It is an object of the present invention to provide an improved perforating machine which will operate at high speeds smoothly and accurately to perforate the work and which at the same time can readily be adjusted for various operating conditions. To this end, and as illustrated, the invention provides a perforating machine having a relatively movable anvil and punch together with mechanism for removing the waste material resulting from operations of the punch. To this end, and as shown, the punch is provided with a recess adapted to receive the waste material, there being a suction device connected with the recess for removing the material to a convenient receptacle.

The invention further contemplates the provision of mechanism for controlling the extent of transverse movement of the punch in advancing work across the face of the anvil, as well as auxiliary driving mechanism for the backing strip when the punch oscillating mechanism is rendered inoperative.

These and other features of the invention are disclosed in the accompanying drawings and in the following detailed specification and will be pointed out in the claims.

In the drawings,

Fig. 1 is a front elevation of a perforating machine illustrating one embodiment of our invention;

Fig. 2 is a side elevation of the machine;

Fig. 3 represents a vertical section of the machine taken along the line III—III of Fig. 1;

Fig. 4 is a perspective view of portions of the punch bar driving mechanism;

Fig. 5 is a sectional view of a portion of the punch bar driving mechanism taken along the line V—V of Fig. 2;

Fig. 6 is a side view partly in section of the punch and its associated driving mechanism;

Fig. 7 is a plan view partly in section of a portion of the punch bar and punch bar frame;

Fig. 8 is a perspective view of part of the mechanism for rotating the punch;

Fig. 9 is a side elevation of a portion of the punch feeding mechanism;

Fig. 10 is a transverse section through a portion of the punch and punch bar frame;

Fig. 11 is a view partly in section of a portion

of the punch feed control mechanism taken along the line XI—XI of Fig. 9;

Fig. 12 is a view in side elevation illustrating the gages and their operating mechanism;

Fig. 13 is a plan view partly in section of a portion of the gage operating mechanism;

Fig. 14 is a view in side elevation of the machine illustrating the anvil with the table removed;

Fig. 15 is an end view of the portion of the machine shown in Fig. 14;

Fig. 16 is a detail view partly in section of the strip feeding mechanism taken along line XVI—XVI of Fig. 9; and

Fig. 17 is a view partly in section of the suction punch operating mechanism.

As shown in Fig. 1 of the drawings, the machine comprises a frame 10 which supports a work table 12 and has an arm 14 overlying the table. Mounted upon the arm is a punch 16 carried by punch bar 18 which is arranged for movement heightwise of the frame to perform punching operations upon work located upon the table and movable longitudinally of the frame for advancing the work step-by-step across the table between punching operations.

The upper portion of the frame 10 has bearings for a horizontal drive shaft 20 which extends from left to right of the machine, as shown in Fig. 1. The drive shaft 20 has secured on its right-hand end a drive pulley 22 by which it may be rotated and has associated with it a starting and stopping mechanism, not illustrated in detail, by which the shaft 20 may be caused to complete either a single or a plurality of revolutions. The drive shaft 20 may be conveniently driven through a variable speed driving device at speeds varying between about 400 and 800 revolutions per minute according to the nature of the work being operated upon. The maximum and minimum speeds may, of course, be other than above stated to suit the operator or the work to be operated upon.

Upon one side of the arm 14 of the frame there is secured a bracket 24, Fig. 2, which supports various parts of the machine. The driving shaft 20 extends through the bracket 24 and carries on its forward end two cams 26 and 28, Figs. 1 and 4, arranged side by side, which are engaged, respectively, by two rolls 30 and 32 carried by a punch lever 34. The cam 28 acts through the roll 32 to actuate the punch lever 34 to depress the punch 16 to punch the work while the other cam 26 acts to determine the amount of lift of the punch during the feeding of the work by the

punch. The roll 30 is rotatably mounted on an eccentric portion 36 of a horizontal stud 38 extending from left to right of the machine and rotatably mounted in the punch lever 34, which 5 stud also has rotatably mounted concentrically on it the cam roll 32. The roll 30 controls the lift of the punch 16 for the work feed and by rotating the stud 38 in the lever 34 the amount 10 of lift of the punch may be varied without affecting the heightwise position of the punch at the end of its punching stroke. The stud 38 is rotated by means of a screw 40 threaded through an upwardly projecting part 42 of the punch lever 34 and engaging an upwardly projecting 15 arm 44 on the stud 38, the arm being held against the screw 40 by a spring-pressed plunger 46 in the punch lever 34 which engages a downwardly extending arm 48 on the stud 38.

The punch lever 34 extends from the cam rolls 20 30, 32 substantially horizontally forwardly and is pivoted about midway of its length on an eccentric portion 50 projecting from an end of a horizontal shaft 52, Figs. 2 and 5, rotatably mounted in the overhanging arm 14 of the machine frame. The shaft 52 has extending upwardly from it an arm 54 by which it may be rotated and the arm 54 has extending laterally from it to the right a lug 56 through which is threaded a substantially vertical screw 58 which 25 has a conical point arranged to engage a V-shaped groove 60 in a plate 62 secured to the arm 14. The bottom of the V-shaped groove is concentric with the axis of the shaft 52 and the engagement of the screw 58 with the groove locks 30 the shaft 52 in adjusted position. By rotating the shaft 52 the heightwise position of the punch 16 at the end of its punching stroke may be adjusted without affecting the amount of lift of the punch during work feeding movement of the 40 punch.

As will hereinafter appear the work feeding movement of the punch 16 may be stopped when it is desired to perform, so called, spot punching in which a workpiece is presented to the machine 45 and the machine is caused to perform a single punching operation upon the work at a selected place. When spot punching is being performed it is desirable that, when the machine stops with the punch raised, the punch shall be comparatively close to the work so that the operator can with accuracy locate the work relatively to the punch. Means is therefore provided whereby the lift of the punch when the machine stops is limited and is less than it normally is when the 50 work is being fed by the punch. This means comprises a screw 64 adjustably mounted in a bracket 66 secured to the forward end of the bracket 24 and arranged to engage a lug 68 projecting from the forward end of the punch lever 60 34 and to limit its upward movement. When the machine is used in the normal manner and the work is being fed step-by-step by the punch the screw 64 is preferably withdrawn from the path of the lug 68 and the punch depressing cam 28 65 then controls the lift of the punch during the return of the punch after feeding. Thus the mechanism above described provides means whereby the heightwise position of the punch at the end of its punching stroke when it is raised 70 during its feeding movement, and when it is raised above the work after punching and feeding or after punching without feeding, may be adjusted independently.

The punch lever 34 at its forward end has 75 rotatably mounted on it a horizontal stud 69, ex-

tending transversely of the machine, upon which is mounted a roller 70 which is engaged by a horizontal face 72 on the upper end of the punch bar 18. The punch bar 18 is vertically slideable in a punch bar frame 74, Figs. 1, 2, 6 and 7, and is urged upwardly into engagement with the roller 70 by a compression spring 76 engaging at its upper end the upper wall of a recess 77 in the punch bar 18 and at its lower end a bracket 78 projecting into the opening and secured on 10 the punch bar frame 74 by screws 75.

The punch bar frame 74 is supported on the lower ends of a pair of parallel arms 80 and 82, Figs. 2 and 5, arranged behind the punch and pivoted on the bracket 24 on the overhanging 15 arm 14 of the machine frame so that as the arms 80 and 82 swing, the punch bar frame 74 is moved substantially horizontally forwardly and rearwardly of the machine. The arms 80, 82 are forked at their lower ends and a rearwardly extending portion 84 of the punch bar frame 74 extends between the forks and is pivoted thereto by horizontal pins 86 and 88 extending transversely of the machine. The forward arm 80 is formed on the left-hand end of a horizontal feed shaft 90 which is rotatably mounted in the fixed bracket 24 and in the machine frame and this shaft is operated by mechanism hereinafter described to move the punch bar frame 74 forwardly and rearwardly. The rear arm 82 is secured on the left-hand end of a horizontal shaft 92 parallel to the shaft 90 and rotatably mounted in the said fixed bracket 24. The rear arm 82 has extending upwardly and rearwardly from its hub an arm 94 which 35 as will hereinafter appear is connected to operate a paper feed mechanism of the machine.

The punch bar 18, Figs. 6 and 7, is slideable vertically in a dovetailed guideway in the punch frame 74 and has a lug 96 projecting forwardly 45 from it in which is rotatably mounted a vertical sleeve 98. The sleeve 98 has formed on its lower end a flange 100 to which is secured a punch carrying block 102. The flange 100 engages the lower end of the lug 96 and the sleeve 98 has 50 secured on its upper end a collar 104 which engages the upper face of the lug 96 so that the sleeve 98 is prevented from endwise movement in the lug but can rotate therein. The punch block 102 is secured to the flange 100 by a screw 106 passing through the sleeve 98 and clamping the collar 104 to the sleeve 98. The collar 104 has projecting rearwardly from it lugs 108, Fig. 8, having between them a vertical recess 109 the upper edges of the walls of which are beveled as 55 shown at 110. When the punch bar 18 is raised the recess between the lugs 108 receives the lower portion of the bracket 78.

When the punch bar 18 is lowered during the punching of the work the recess between the 60 lugs 108 leaves the bracket 78 and the punch can be turned about the axis of the sleeve 98 if the work is swung during the work feed. When the punch is finally lifted from the work the engagement of the beveled walls of the recess 109 with the bracket 78, if the punch has been turned, rotates the punch to its normal position. To prevent rotation of the punch as it descends the collar 104 also has a lug 112 projecting from it, the lug having a vertical recess 114 which 70 when the punch is fully raised is engaged by a vertical spring-pressed plunger 116, Figs. 1 and 7, projecting downwardly from a lug 118 on the punch bar frame 74. When the punch bar 18 is depressed to punch the work the recess 114 is 75

the lug 112 leaves the plunger 116 and the lug 109 is then just below the lower end of the plunger 116. At the end of the feed, during which the lug 112 remains below the plunger 116, if the punch has been turned and moved the recess 114 out of line with the plunger 116 the lug 112 will engage the spring plunger 116 as the punch bar 18 rises and will lift the spring plunger until one of the beveled walls 110 on one of the lugs 108 engages the bracket 78 on the punch bar frame and rotates the punch to normal position after which the spring plunger 116 snaps down into the recess 114 in the lug 112.

The block 102 has secured to its lower face a punch consisting of two small plates 120 and 122, Fig. 6, secured together, the lower plate 120 carrying small tubular punches 124 which abut against the underside of the upper plate 122. The plates 120 and 122 are secured together by screws 125 arranged behind the punches. The punches themselves are arranged as close as possible to the front edges of the plates so that the operator has as clear a view as possible of the portion of the work being punched. The side edges of the plates 120 and 122 are beveled and are secured in a dovetailed guideway 126, Fig. 1, formed partly in the punch block 102 and partly in a clamp plate 128 secured to the punch block by a screw 130 thereby to secure the plates in position. The punch block 102 has formed in it a passage 132, Fig. 6, communicating with the tops of the punches to allow removal of the pills cut from the work by the punches. The passage 132 extends rearwardly to an arcuate face 134 (Fig. 10), formed on the punch block 102 which face is concentric to the axis of the vertical sleeve 93 about which the punch turns. The arcuate face 134 is in engagement with an arcuate face 136 formed on a downwardly extending portion of the punch bar frame 74 which portion has formed in it a passage 138 connected by a tube 140 and a flexible pipe 142 (Fig. 2), to an extracting mechanism hereinafter described.

The mechanism for actuating the punch bar frame 74 to cause the punch to feed the work includes an arm 143, Figs. 3 and 9, secured on the rear end of the feed shaft 90 which, as above set forth, has on its forward end the depending arm 80 which is pivotally connected to the punch bar frame 74. The arm 143 has pivotally connected to it by a horizontal pin 144 one end of a link 146. The other end of the link 146 is pivotally connected at 148 to the rear end of a link 150 (Fig. 3) and to the lower end of a link 152. The forward end of the link 150 is pivotally connected at 154 to a cam lever 156 pivoted on a horizontal shaft 158 secured in the machine frame. The cam lever 156 has on it a cam roll 159 which enters a cam groove 160 in a cam 162 secured on the driving shaft 20. The upper end of the link 152 is pivotally connected to a feed adjusting lever 164 which at its rear end is rotatably mounted on a horizontal shaft 166 secured in the machine frame. When the cam lever 156 is actuated by its cam 162 the link 152 swings about its pivotal connection to the feed adjusting lever 164 and the path of movement of the pivot 148 of the three links 146, 150 and 152 is thereby controlled and its position and direction may be changed by adjustment of the adjusting lever 164. This changing of the position and direction of the path of movement of the pivot 148 of the three links varies the amount of oscillating movement given by the cam lever 156 through the links 150, 146 to the arm 143 on the feed shaft 90 and there-

fore to the punch bar frame 74. When the punch bar frame 74 is at the forward end of its feeding movement the pivotal connection 144 of the link 146 and arm 143 on the feed shaft 90 is in axial alinement with the pivotal connection 154 of the link 150 and cam lever 156, as shown in Figs. 3 and 9, and the feed adjusting lever 164 may be adjusted without moving the punch bar frame 74. The punch therefore always commences to feed the work from the same position. When the feed adjusting lever 164 is moved to the lower end of its range of adjustment a maximum feed of about three-quarters of an inch is imparted to the punch and when the feed adjusting lever 164 is moved to the upper end of its range of adjustment the pivotal connection 148 of the three links 146, 150, 152 is brought into axial alinement with the pivot 158 of the cam lever 156 and movement of the cam lever does not move the punch bar frame. When the work feed is cut out in this manner, spot punching may be conveniently performed as it is not necessary or desirable that the work shall be fed.

The maximum feed when the adjusting lever 164 is moved to the lower end of its range of movement may if desired be reduced to about half an inch and for this purpose the pivotal connection between the arm 80 and the punch bar frame 74 may readily be moved nearer the pivot of the arm by withdrawing the pin 88 connecting the arm 80, and punch bar frame 74 and placing it in a hole 168 (Fig. 2) provided in the arm and punch bar frame nearer the pivot of the arm. This variation in the maximum feed gives greater accuracy in the feed of the work and tends to lighten the strain on the mechanism as compared with obtaining a half inch feed by adjustment of the feed adjusting lever as, of course, could be obtained when the maximum feed is about three-quarters of an inch, an amount which is seldom required.

The forward end of the feed adjusting lever 164 has secured on it an arcuate plate 170 the front face of which moves behind a fixed pointer 172, Figs. 1, 2, 5, and 14, as the lever is adjusted upwardly or downwardly and has on it graduations which indicate the amount of feed obtained according to the position of the lever. The graduations are at opposite edges of the plate 170 and the graduations along the left-hand edge (Fig. 1) indicate the amount of feed with the pin 88 in the outer hole in the arm 80 and punch bar frame and the graduations along the right-hand edge indicate the amount of feed when the said pin is in the inner hole 168 in the arm and frame. The feed adjusting lever 164 is clamped in adjusted position to an arcuate plate 174, secured to a bracket 176 secured on the overhanging arm 14 by a bolt 178 (Fig. 11) and hand nut 180 on the lever which clamp the lever against the plate 174.

The illustrative machine is provided with three presser feet 182, 184 and 186 (Figs. 1 and 12) to hold down the work during the punching of the work. The presser feet are arranged to engage the work at the right and left of the punch and behind the punch. The presser foot 184 is carried by the presser foot 182 and the presser feet are all independently adjustable horizontally toward or from the punch. The presser feet 182, 186 are carried by a presser foot bar 188 which is slidable vertically in the bracket 66 secured to the bracket 24 fixed on the end of the overhanging arm 14 of the machine frame. The bar 188 is urged downwardly by a spring 190 in the upper end of the bar the upper end of which

spring engages a plate 192 secured on the presser bracket 66. A key 194 projecting laterally from the bar 188 enters a vertical slot 196 in the bracket 66 and prevents the bar from twisting in the bracket. The presser feet are raised from the work while the work is being fed by a cam lever 198 pivoted about midway of its length on an end of a horizontal spindle 200 secured in the bracket 24. The cam lever 198 extends forward-
 10 ly from its pivot and its forward rounded end 202 engages the walls of a slot 203 in the presser bar 188. The cam lever 198 at its rear end has mounted on it a cam roll 204 which is held in engagement with the underside of a cam 206 on the
 15 left-hand end of the driving shaft 20 by the presser bar spring 190. The cam 206 causes the cam lever 198 to raise the presser feet after the work has been punched and holds the presser feet raised while the work is being fed after which
 20 the presser feet are lowered on to the work while the punch is raised and returns.

The presser feet may be raised to allow the work to be presented to the machine by a treadle actuated arm 208 (Fig. 2) secured on the left-hand end of a horizontal shaft 210 extending transversely of the machine and rotatably mounted in the fixed bracket 24 on the overhanging arm 14 and in a bracket 212 (Fig. 3) secured to the machine frame. The shaft 210 also has secured to it an arm 214 which is connected by a rod 216 to a treadle. The treadle actuated arm 208 engages the rear end of the cam lever 198 when the treadle is depressed and moves the cam roll 204 away from its cam 206 and raises the
 35 presser feet.

The illustrative machine is provided with an edge guide 218 (Fig. 1) at the right-hand side of the punch 16. The edge guide is formed on the lower end of an arm 220 which extends upwardly and to the right from the edge guide. The right-hand end of the arm 220 is pivoted on a vertical stud 222 (Fig. 13) secured in an adjustable block 224. The arm 220 has extending forwardly from it an arm 226 which has formed on it an inclined face 228 (Fig. 1) arranged to be engaged by the pointed lower end of a screw 230 adjustably mounted in the block 224. The face 228 is held against the screw 230 by a leaf spring 232 secured on the block 224 and bearing against the
 40 arm 226. By adjusting the screw 230 the edge guide may be moved forwardly or rearwardly of the machine in relation to the punch. The edge guide arm 220 has pivoted on it a blade spring 234, beneath which the edge of the work passes, the left-hand end of which spring is just above the upper face of a paper strip hereinafter referred to. The left-hand end of the blade spring 234 may be adjusted upwardly or downwardly by a thumb screw 236 threaded through a lug 238 on
 45 the edge guide arm 220 and engaging an inclined face 240 on the blade spring which is held against the screw by a spring 242. The adjustable block 224 aforesaid has threaded engagement with a horizontal sleeve 244 rotatably mounted on a horizontal spindle 246 which is secured in a trunnion block 248 and extends from left to right of the machine. The sleeve 244 is prevented from moving endwise on the spindle 246 by a flange 250 on the spindle, and a nut 252 on a threaded portion
 50 of the spindle. The sleeve 244 has formed on it a knurled flange 254 by which the sleeve may be rotated to move the edge guide arm 220 toward or from the punch. The spindle 246 is secured in the trunnion block 248 by a clamp screw 256 in
 55 the block and the spindle and edge gage may be

quickly adjusted toward or from the punch by loosening the screw and moving the spindle and edge guide bodily toward or from the punch. The threaded sleeve 244 provides a fine adjustment of the edge guide position. The adjustable block 224 is prevented from rotating with the sleeve 244 by a horizontal pin 258 secured in the block 224 which extends through an open ended slot in the trunnion block 248. The trunnion block 248 is pivotally mounted on the lower end 10 of an arm 260 which is pivoted at 261 on the bracket 66. The pivot of the trunnion block 248 and the pivot of the arm 260 are horizontal and when viewed from above the machine extend rearwardly and to the right at an angle of about 15 thirty degrees to the direction of feeding movement of the punch. The trunnion block 248 has secured on it a guide rod 262 which extends upwardly and to the right from the block. The guide rod 262 also extends forwardly at right 20 angles to the pivot of the trunnion. The outer end of the guide rod 262 is slidably mounted in a swivel block 264 having a rearwardly extending horizontal stem rotatably mounted in the machine frame. When the depending arm 260 is 25 swung upwardly toward the right the edge guide and associated parts are swung away from their operative position upwardly and toward the right and forwardly of the machine. The upward movement to the right is provided to move the 30 edge guide out of the way when spot punching is being performed or the punch is being changed. As the edge guide is swung away from its operative position the rod 262 and swivel block 264 cause the arm 260 and trunnion block 248 to move 35 relatively and the trunnion block and parts carried thereby to maintain substantially the same angular relationship in the machine and cause the edge guide to be raised without engaging adjacent parts of the machine beneath it. When the edge guide is moved away from its operative position its adjustment is not altered.

The base portion of the machine frame has secured at its forward end an anvil 266 (Figs. 1 and 2) against which the punch 16 operates. A 40 paper strip 268 passes over the anvil and is preferably fed along as the work is fed. The punch cuts into the paper strip during the punching and is raised, as hereinbefore described, during its work feeding movement just above the strip. The 45 paper strip 268 passes substantially horizontally from the rear of the machine beneath the rear end of the base of the frame and then upwardly through a bent tube 270 having a rectangular passage to guide the paper. The tube extends 50 from below the anvil and up in front of the anvil and guides the paper strip on to the anvil. The tube 270 is secured to the machine frame by a screw 272 in a slot 274 and may be adjusted to the right or left across the path of feed movement of the punch to position the strip laterally in relation to the punch. After passing over the anvil the paper strip passes down behind the anvil around two guide pulleys 276 mounted on the machine frame and then substantially horizontally toward the rear.

The table 12 is in the form of a flat plate having its upper surface level with the top of the anvil 266 and upon which the work can be spread out flat as it is fed over the table by the punch. If work of a more or less tubular nature, such as a closed shoe upper, is to be operated upon the table may be removed and a cover 278 (Figs. 14 and 15) secured on the machine frame in place thereof. The cover 278 shrouds the paper strip guiding 55

rolls 276 and tube 270 and the cover 278 and left-hand end of the base portion of the frame provide a post or arm over which a work piece may be placed and pass down at each side of and if necessary beneath the post or arm. The cover 278 is secured on the machine by a pin 280 extending horizontally from the cover which enters a bore in the frame and a spring clip 282 secured on the cover which engages the frame and the 10 cover may be removed by merely withdrawing it to the left from the frame. The upper face of the cover is level with the top of the anvil and has in it a recess to receive the anvil.

The table 12 has depending lugs 284 and 286 (Fig. 2) through which and through the frame passes a rod 288. The rod 288 is held in position by a spring plunger 290 in the lug 286 the end of the plunger entering a groove on the rod. The table also has depending lugs 292 one at each side 20 of a lug 294 on the frame. The lugs 292 have in them recesses 296 arranged to engage a pin 298 in the lug 294. When the rod 288 is withdrawn by means of a knurled head 300 on the rod the table can be readily withdrawn from the machine.

The paper strip 268 is carried by a reel 302 (Fig. 2) secured on a horizontal spindle 304 extending from left to right of the machine and rotatably mounted in one arm of a lever 306 which 30 is pivotally mounted at 307 on a paper reel frame 308 secured to a bracket 310 fixed to the base of the frame 10 behind the machine. The paper strip 268 passes from this reel under and over the anvil 266 and from the anvil is wound on a 35 second reel 312 secured on a horizontal spindle 314 rotatably mounted in the other arm of the lever 306. When the strip has been wound from one reel to the other the lever 306 may be swung to reverse the positions of the reels and the paper 40 may be used again. A spring plunger 316 mounted in the paper reel frame 308 is arranged to engage either of two recesses 318, one at each end of the lever 306 to hold the lever in one or the other of its positions. The paper strip is drawn 45 over the anvil by an intermittently rotated feed roll 320. The feed roll 320 is mounted on the paper reel frame 308 and the paper strip is pressed against the feed roll by a presser roll 322 rotatably mounted on a substantially horizontal arm 324 extending forwardly and rearwardly of the machine and pivoted at its rear end on a stud 326 secured in the paper reel frame 308. The presser roll 322 is pressed upwardly against the paper strip by a spring plunger 328 carried in the paper 50 reel frame 308 and engaging the under side of the arm 324. The arm 324 and presser roll 322 may be pressed down to allow the paper strip to be passed between the feed roll 320 and presser roll 322 and held down by a spring latch 330 on the 55 arm 324 which engages a projection 332 on the paper reel frame 308. When the paper strip 268 leaves the reel 302 it passes underneath a roll 334 rotatably mounted on the stud 326 and between a face 336 on the arm 324 and a roll 338 carried 60 by an arm 340 pivoted on the stud 326. The roll 338 is pressed against the strip by a spring 342 engaging the arm 340 and a lug 341 on the paper reel frame 308. As the paper strip is drawn over the anvil by the feed roll 320 the roll 338 and face 65 336 exert a drag on the strip 268 and this ensures that the strip will be flat on the upper face of the anvil 266. The paper strip feed roll 320 is in the form of a ring and is mounted on an inner member 344 rotatably mounted on a spindle 346 secured in the paper reel frame 308. The member

344 has formed in it recesses 348 having faces 350 between which and the inner face of the roll 320 are spring pressed rollers 352. When the member 344 is rotated in a clockwise direction in Fig. 2 the rollers 352 are gripped between the faces 350 and inner face of the roll 320 and the member and roll rotate together. When the member 344 is rotated in the opposite direction the rollers 352 travel with it but tend to move toward the enlarged ends of the recesses 350 and fail to grip the 10 feed roll, frictionally held against movement as will hereinafter appear, and the feed roll is not rotated. The member 344 is actuated by a rod 354 connected to the aforementioned upwardly and rearwardly extending arm 94 of the rear 15 punch bar frame supporting arm 82 and connected to the member. Return movement of the feed roll is prevented by a friction block 356 carried by the paper reel frame 308 and pressed against the roll by a spring 358. The arm 94 has 20 formed in it a radial groove 360 in which is adjustably secured a stud 362 to which the rod 354 is pivoted so that by adjusting the stud 362 toward or from the pivot of the arm 94 the amount of movement imparted to the feed roll and paper 25 strip may be varied. If the stud 362 is so positioned in the groove 360 that the feed of the paper strip is equal to the feed of the work any adjustment of the feed of the work will correspondingly vary the feed of the paper strip. The stud 362 30 may, however, be adjusted in the groove 360 so that the feed of the paper strip is less than the feed of the work, which may be desirable so that when a comparatively long work feed is being used the paper strip may by being fed a less distance be more fully used up.

When the feed of the work is stopped and the machine used for spot punching as hereinbefore referred to the feed of the paper strip by the means above described will also be stopped. It 40 may be desirable, however, to feed the paper strip under the punch when spot punching is being performed so as to present a fresh portion of strip beneath the punch for each punching operation. To this end, the paper strip is fed, 45 when the work feed is stopped, by removing the stud 362 on which is pivoted the upper end of the rod 354 and inserting it in a radial groove 364 (Fig. 2) in an arm 366 fixed on a horizontal shaft 368 (Figs. 2 and 9) rotatably mounted in the machine frame and extending from left to right of the machine. An arm 370 fixed on the shaft 368 is connected by a link 372 to an arm 374 pivoted on a sleeve 376 on the cam lever 156. The cam lever 156 and arm 370 may be connected 50 together by a spring plunger 378 (Fig. 16) in a boss 380 on the arm 374 which enters an opening 382 in the cam lever 156 so that the paper strip feed clutch is operated by the cam 162 instead of by the work feed mechanism and may be varied 55 by adjusting the upper end of the rod 354 in the groove 364 in the arm 366. The spring plunger 378 has on it a head 384 from which project parallel to the plunger two lugs 386 arranged when the plunger 378 is in engagement with the 60 opening in the cam lever 156 to lie at each side of the boss 380 on the arm 374. When the plunger is withdrawn it may be rotated so that the lugs engage the face of the boss and hold the plunger 65 out of engagement with the opening in the cam lever. 70

The upper paper strip reel spindle 314 (Fig. 2) has secured on it a pinion 388 which meshes with a gear 390 (Figs. 2 and 17) secured on a shaft 392 rotatably mounted in the paper reel frame 75

308. The shaft 392 has secured on it a flanged sleeve 394 on which is rotatably mounted a pulley 396 driven by a belt from the driving shaft of the machine. The pulley is pressed against a friction washer 398 on the flanged sleeve by a spring 400 surrounding the shaft 392 which spring is confined between a nut 402 and a collar 404 on the shaft, the spring pressing a friction washer 406, between the collar 404 and the pulley, against the pulley. The shaft 392 is therefore frictionally driven. The spindle 304 (Fig. 2) of the paper reel 302 has secured on it a pinion 408 which when the lever 306 is rotated as aforesaid to reverse the positions of the paper reels moves 15 into engagement with the gear 390 and the reel 302 is driven.

The pieces of material punched from the work are removed from the machine by a suction device which includes a suction pump consisting of a 20 circular casing 410 (Figs. 2 and 18) formed in two parts having clamped between the parts a circular leather disk 412 so that there is a space in the casing at each side of the disk. The casing 410 is secured to the bracket 24 and at the 25 center of its left-hand side is connected by a pipe 414 to an air-tight receptacle 416 (Fig. 3) on the bracket 310. The receptacle 416 is also connected by the flexible pipe 142 to the punch block 102 as hereinbefore described. The leather disk 30 412 in the casing is secured at its center to a horizontal pump rod 418 slidably mounted in the casing 410 and pressed in one direction by a spring 420 on the rod which is confined between the casing 410 and a collar 422 secured on the rod. 35 When the leather disk is actuated by the spring 420 a suction is exerted through the receptacle 416 and pipes 414 and 142 connected to it to the air in the passage 132 in the punch block 102 to draw therefrom and deposit in the receptacle 40 pieces cut from the work by the punch. The collar 422 on the pump rod 418 is engaged at its side opposite to the spring by an arm 424 of a cam lever 426 which is pivoted on a vertical pivot 428 on the paper reel frame 308. Another arm 430 of the cam lever 426 engages an open cam face on a cam 432 which is secured on a horizontal shaft 434 (Figs. 2 and 17) rotatably mounted in the paper reel frame 308. The shaft 434 has secured on it a gear 436 (Fig. 2) which 45 meshes with a gear 438 secured on the aforesaid pulley 396 and makes one revolution to about five of the driving shaft 20 of the machine. The cam 432 is in the nature of a spiral with a sudden drop so that the pump spindle 418 is moved comparatively slowly against the action of its spring and then suddenly released so that its spring can act to create the suction. A flap valve 440 is arranged on the casing to allow air in the casing on the side of the leather disk 412 adjacent the pipe 60 414 to escape as the disk is actuated by the cam 432.

In the operation of the machine a shoe part blank such as a tip to be perforated is located upon the table 12 with the edge of the blank in 65 engagement with the edge guide 218 and is moved beneath the oscillating punch 16, the presser feet 182, 184 and 186 being raised at this time by means of the treadle actuated arm 208 (Fig. 2) to permit insertion of the work. The punch 70 perforates the work utilizing the paper strip 268 on the anvil 266 as a backing and moves rearwardly to feed the work, after which the presser feet hold the work stationary while the punch is raised and returned to position to perform another 75 punching and feeding operation, this cycle being

repeated until a row of perforations has been formed along a marginal portion of the blank. The length of the feed stroke of the punch is regulated as required by varying the position of the index plate 170, Fig. 1. The backing strip 5 268 is advanced over the anvil, in timed relation to feed movements of the punch, by the feed roll 320 (Fig. 2), which draws the strip from the reel 302, the strip being wound on to the reel 312 which is driven by the gear 390. After each 10 punching operation the resulting pills which enter the cavity 132, Fig. 6, of the punch are withdrawn through the tube 140 by means of the suction pump 410 (Fig. 18).

Having described our invention, what we claim 15 as new and desire to secure by Letters Patent of the United States is:

1. In a perforating machine, an anvil, a backing strip adapted to be advanced across the face of the anvil, means for sustaining the backing strip comprising a pair of reels, an arm pivotally mounted upon the frame of the machine, and upon which the reels are mounted, intermittently operated mechanism for advancing the strip across the face of the anvil, a gear for driving 20 one of the reels, each of the reels having a pinion adapted to engage the gear, and means for locating a selected reel with its pinion in engagement with the gear.

2. A perforating machine comprising an anvil, a punch mounted for reciprocation relatively to the anvil for perforating work positioned thereon, a backing strip extending across the face of the anvil, means for oscillating the punch laterally of the anvil to feed the work, means for feeding the backing strip across the face of the anvil comprising a roll operatively connected to the punch oscillating means, and auxiliary means for driving the roll when the punch oscillating means is not in operation.

3. A perforating machine comprising an anvil, a punch mounted for reciprocation relatively to the anvil to perforate work positioned thereon, a backing strip extending across the face of the anvil, means for advancing the strip across the anvil comprising an intermittently power-driven roll, a second roll pivotally mounted upon the frame of the machine, means for forcing the second-mentioned roll and the backing strip toward the power-driven roll, and a manually operated latch adapted to hold the second-mentioned roll in inoperative position.

4. In a perforating machine, an anvil, a punch mounted for reciprocation heightwise of the anvil to perforate material positioned thereon, means 65 for advancing the punch transversely of the anvil to feed the work comprising a power-driven cam, a cam lever, a plurality of links operatively connected with the cam and with the punch, means for moving the links into neutral position in 70 which the cam is not effective to advance the punch, a backing strip positioned upon the anvil, means for feeding the backing strip across the face of the anvil normally operative in timed relation to the punch feed, and an auxiliary backing strip feeding means adapted to be connected to the cam when the means for feeding the punch is in neutral position.

5. In a perforating machine, an anvil, a punch bar carrier, a punch bar slidably mounted in the 75 carrier for movement heightwise of the anvil, a punch carried by the punch bar and adapted to perforate work positioned upon the anvil, means for moving the punch transversely of the anvil including a pair of links pivotally mounted 80

upon the frame of the machine and pivotally connected to the punch bar frame, an oscillatory shaft mounted upon the frame and connected to one of the links, a feed control lever pivotally mounted upon the frame and carrying a pivot, a power-driven cam, a cam lever engaging the cam and operatively connected to the pivot and to the links whereby the extent of oscillation of the shaft in response to operation of the cam 10 is varied in accordance with the position of the feed control lever.

6. A perforating machine comprising an anvil, a punch mounted for movement heightwise of the anvil to perforate work positioned thereon, a cam, means operatively connecting the cam and the punch for advancing the punch transversely of the anvil to feed the work, a backing strip positioned upon the anvil, means normally connected with the punch advancing means to 15 feed the backing strip across the face of the anvil, and independent means adapted to connect the cam and backing strip feed mechanism for feeding the backing strip when the punch feed is inoperative.

25 7. A perforating machine comprising an anvil, a punch bar frame, a punch bar slidably mounted in the frame, and a punch carried by the bar for perforating work positioned upon the anvil, a plurality of links pivotally mounted upon the 30 frame of the machine and connected with the punch bar frame for advancing the punch across the face of the anvil, and means for driving the links adapted to be connected selectively to the punch bar frame at one or another of a 35 plurality of points for varying the extent of movement of lateral movement of the punch.

40 8. A perforating machine comprising an anvil, a punch mounted for reciprocation relatively to the anvil to perforate work positioned upon the anvil, means for advancing the punch across the face of the anvil to feed the work, the punch having a recess therein for receiving waste material removed from the work, a receptacle for the waste material, means connecting the recess 45 with the receptacle, a suction pump operatively connected to the receptacle, and cam-operated means for operating the pump to cause removal of the waste material from the recess.

9. A perforating machine comprising an an-

vil, a punch bar mounted for reciprocation heightwise of the anvil, a punch bar carrier mounted for movement transversely of the anvil, a punch pivotally mounted upon the punch bar and having a recess adapted to receive waste 5 material removed from the work, the punch having also an arcuate bearing surface adjacent the recess, the punch bar carrier having a corresponding arcuate shaped bearing surface, a passageway in the punch bar extending through 10 the arcuate surface in alinement with the recess, a suction pump, and means connecting the suction pump with the passageway and recess.

10. A perforating machine comprising an anvil, a punch mounted for reciprocation relatively 15 to the anvil to perforate work positioned thereon, a punch carrier mounted for oscillation in the frame of the machine, means for mounting the punch in the punch carrier for movement of rotation relatively thereto, the punch having a 20 recess therein adapted to receive waste material removed from the work, a passageway in the punch carrier in alinement with the recess, and a suction device operatively connected with the 25 passageway for removing the waste material from the punch.

11. A perforating machine comprising a frame, an upwardly projecting arm on the frame, an anvil mounted upon the arm, a punch movable heightwise of the frame for perforating work 30 positioned upon the anvil, a table surrounding the anvil and having at the rear portion thereof means for releasably engaging a portion of the frame, a pair of depending lugs on the table adjacent the arm, an opening in the frame in alinement with the lugs, and a rod passing through the opening and through the lugs to detachably 35 secure the table in position.

12. A perforating machine having a frame, an upwardly projecting arm upon the frame, an anvil mounted upon the arm, a punch mounted for movement relatively to the anvil for perforating work positioned thereon, a backing strip arranged to pass over the anvil, a backing strip guiding means mounted upon the arm, and a cover secured to the arm and surrounding portions of the 40 anvil and strip guiding means. 45
